SHOE

Charles J. Jannings, Union, Mo.

Application November 29, 1937, Serial No. 176,971

6 Claims. (Cl. 36—24.5)

This invention relates to improvements in shoes, one of the objects being to reinforce a shoe structure at the junction of the heel and outer sole. A further object is to provide a very simple and inexpensive reinforcing device that can be easily and quickly positioned in the shoe structure, and which cooperates with other elements of the shoe to resist the stresses tending to separate the heel from the soles. More specifically stated, an object is to accomplish these results through the medium of a stiff brace or support firmly interlocked with the heel, and extending from the breast of the heel to provide a firm seat for the shank portion of the outer sole.

In one form of the invention, this shank brace is a simple piece of sheet metal, or other stiff sheet material, having a concealed portion interlocked with the heel and outer sole, and an extended portion exposed below the outer sole. The interlocking elements firmly unite the heel with the brace and the outer sole, at the same time providing a firm anchorage for the overhanging seat which lies immediately below the outer sole. When thus united and braced at the junction of the heel and outer sole, the several elements are well adapted to withstand the frequent shocks tending to "kick" the heel from the soles.

With the foregoing and other objects in view, the invention comprises the novel construction, combination and arrangement of parts herein-after more specifically described and shown in the accompanying drawing, which illustrates one form of the invention. However, it is to be understood that the invention comprehends changes, variations and modifications within the scope of the claims hereunto appended.

Fig. 1 is a side view, partly in section, illustrating a shoe embodying the features of this invention.

Fig. 2 is a detail view of a heel having a recess to receive the stiff brace.

Figure 3 is a detail view of the brace, preferably made of metal, or other stiff material, having a flanged rear portion conforming to the recess in the heel.

Fig. 4 is a detail view showing the stiff brace interlocked with the heel.

Fig. 5 is a detail view of a portion of the outer sole having a rear margin adapted to be seated between the stiff brace and a projecting lip which extends from the heel.

Fig. 6 is an enlarged fragmentary section on

the line 6—6 in Fig. 4, with the outer sole added to the structure.

The shoe comprises a heel 1 which may be made of wood, the invention being especially adapted for women's shoes having high heels, 5 which are frequently made of wood. However, the heel may be made of any other suitable material. The inner sole 8 may be attached to the heel in the usual manner by means of a screw 9 and nails 10. An ordinary steel shank 11 piece may be located between the inner sole 8 and the outer sole 12. The upper 13 is attached to the inner and outer soles in any suitable manner.

In making a shoe it is customary to attach both 15 soles to the upper 13, and then attach the heel to soles. However, the rear portion of the outer sole is usually seated upon the top of the heel. In the new structure, the heel is provided with a lip 14 extending from the top of a recess 15 (Fig. 20 20), and the rear margin of the outer sole 12 is seated in this recess, where it lies immediately below the lip 14, as shown in Fig. 1 and Fig. 6.

Attention is now directed to the stiff brace 16 extending from the recess 15 and contacting 25 with the bottom face of the outer sole 12. If desired, this brace may be attached to the sole by means of a nail 17 clinched on the metallic shank piece 11 as shown in Fig. 1, but such attachment is not essential. This brace 16 is 30 firmly seated in the recess 15, and in the preferred form of the invention, it has a flange 18 contacting with the rear wall of the recess. The upper edge of said flange 18 contacts with the lip 14 as shown in Fig. 1, and the rear margin 35 of the outer sole is firmly seated in the brace 16.

Therefore, any downward pressure on the sole in the area near the heel will be very effectively resisted by the brace 16, which is interlocked with the heel. Furthermore, any forward thrusts 40 on the lower portion of the heel are transmitted to the extended brace 16, and thence to a large area of the sole which is seated on said brace. Bearing in mind that the outer sole is firmly 45 attached to the shoe upper, it will also be apparent that rearward thrusts at the bottom of the heel are transmitted through this reinforced area near the junction of the heel and outer sole, and that the simple reinforcement is well adapted 50 to withstand the frequently occurring stresses which tend to separate the heel from the soles.

Attention is now directed to the combination and arrangement of specific details wherein the several elements cooperate with each other in a 55

particular manner to very effectively perform the several functions, at the same time producing a neat and entirely feasible reinforcement lacking certain objections found in previous devices of this kind.

5 The heel has an attaching surface at the top, and the relatively narrow lip 14 is located at the front of this attaching surface, said lip being formed integral with the heel. The attaching 10 surface is recessed at opposite sides of the relatively narrow lip, and the bottom wall of the recess is curved under the lip to provide an approximately crescent-shaped recess at the top of the breast of the heel. The lip 14 has a curved 15 bottom face forming the top wall of the recess. However, this narrow lip 14 is at the middle of the recess, and the top of said recess is open at opposite sides of the lip.

20 The outer sole 12 has an approximately crescent-shaped rear margin which conforms to the recess, as shown most clearly in Fig. 6. At this point, the relatively narrow lip 14 lies directly between the side edges of the outer sole. The interlocked portion of the outer sole is concealed 25 in the recess, so its side edges are not exposed at the side faces of the shoe.

20 The interlocked shank brace 16 has a curved 30 bottom portion seated on the bottom of the recess, and an upturned rear marginal portion 18 located directly between and contacting with the rear wall of the recess and the rear edge of the outer sole 12. This upturned rear margin 18 of the interlocked shank brace has a curved upper 35 edge conforming to and abutting against the curved bottom face of the lip 14. Said interlocked shank brace 16 is also provided with an overhanging support conforming to and extending from the curved bottom of the recess in the heel, so as to form an extended seat for the correspondingly curved outer sole.

40 Downward pressure on this overhanging seat will be firmly resisted by the interlocked portion of the brace 16 as such downward pressure will tend to transmit an upward thrust to the rear 45 marginal flange 18 which is seated against the lip 14 to prevent downward displacement of the overhanging seat.

40 In fact, the brace 16 is so interlocked with the heel and sole that it tends to prevent displacement in all directions, and when the parts are 50 interlocked in this manner, it is not necessary to use nails, or the like, to attach the brace 16 to the shoe. Furthermore, the interlocked portions of the brace 16 and sole 12 are concealed in the 55 recess 15 which extends downwardly from the attaching surface of the heel, so these interlocking elements are not exposed at the sides of the shoe.

60 The simple shank brace shown in Fig. 3 is an inexpensive addition to a shoe, and its several 65 elements are arranged to provide unusual strength in the area near the junction of the heel and outer sole, which very materially increases the durability of the shoe.

I claim:

65 1. In a shoe, a heel having an attaching surface at the top and a lip at the front of said attaching surface, said heel being provided with a recess immediately below said lip, an inner sole secured above said attaching surface, an outer sole having 70 a marginal portion extending into said recess, and a shank brace interlocked with said heel and outer sole, said interlocked shank brace being seated in said recess and provided with an upturned portion abutting against said lip, and said 75 interlocked shank brace being provided with an

overhanging support extending from said recess to form an extended seat for the outer sole.

2. In a shoe, a heel having an attaching surface at the top and a relatively narrow lip at the front of said attaching surface, the said attaching surface being recessed at opposite sides of said relatively narrow lip, the recess being continued under the lip to provide a continuous recess which extends downwardly from opposite sides of said attaching surface, said recess terminating between the opposite side faces of the heel, and the relatively narrow lip being formed directly between the ends of the recess, an inner sole secured above said recessed attaching surface, an outer sole having a marginal end portion seated in said recess, and a shank brace seated between said end portion and the bottom of said recess, said shank brace being provided with an overhanging support extending from said recess in the heel to form an extended seat for the outer sole.

20 3. In a shoe, a heel having an attaching surface at the top and a relatively narrow lip at the front of said attaching surface, the said attaching surface being recessed at opposite sides of said relatively narrow lip, the recess being continued under the lip to provide a continuous recess which extends downwardly from opposite sides of said attaching surface, said recess terminating between the opposite side faces of the heel, and the relatively narrow lip being formed 25 directly between the ends of the recess, an inner sole secured above said recessed attaching surface, an outer sole having a marginal end portion conforming to and seated in said recess, said relatively narrow lip being directly between the side 30 edges of said marginal portion, and a shank brace extending from the bottom of said recess to form an overhanging seat for said outer sole.

4. In a shoe, a heel having an attaching surface at the top and a lip at the front of said attaching surface, the said attaching surface being recessed at opposite sides of said lip, and the recess being continued under the lip to provide a continuous recess at the top of the breast of said heel, an inner sole secured above said recessed attaching surface, an outer sole extending into said recess, and a shank brace interlocked with said heel and outer sole, said interlocked shank brace having a bottom portion seated on the bottom of said recess and an upturned rear marginal portion 50 located between and contacting with the rear wall of the recess and the rear edge of the outer sole therein, said upturned rear marginal portion of the shank brace having an upper edge abutting against the bottom face of said lip, and said interlocked shank brace being provided with a support extending from said recess in the heel to form an extended seat for the outer sole.

5. In a shoe, a heel having an attaching surface at the top and a relatively narrow lip at the front of said attaching surface, the said attaching surface being recessed at opposite sides of said relatively narrow lip, the bottom wall of the recess being continued under the lip to provide a continuous recess at the top of the breast of said heel, said relatively narrow lip being at the middle portion of the recess, an inner sole secured above said recessed attaching surface, an outer sole extending into said recess, and a shank brace interlocked with said heel and outer sole, said interlocked shank brace having a bottom portion seated on the bottom of said recess and an upturned rear marginal portion between the rear wall of the recess and the rear edge of the outer sole therein, said upturned rear marginal por- 70 75 80 85 90 95

tion of the shank brace having an upper edge abutting against said lip, and said interlocked shank brace being provided with a support extending from said recess in the heel to form an 5 extended seat for the outer sole.

6. In a shoe, a heel having an attaching surface at the top and a lip at the front of said attaching surface, the said attaching surface being recessed at opposite sides of said lip, and the 10 bottom wall of the recess being curved under the lip to provide an approximately crescent-shaped recess at the top of the breast of said heel, said lip having a curved bottom face forming the top wall of the recess, an inner sole secured above said 15 recessed attaching surface, an outer sole having a crescent-shaped margin extending into said

crescent-shaped recess, and a shank brace interlocked with said heel and outer sole, said interlocked shank brace having a curved bottom portion seated on the bottom of said recess and an upturned rear marginal portion located directly 5 between and contacting with the rear wall of the recess and the rear edge of the outer sole therein, said upturned rear marginal portion of the shank brace having a curved upper edge conforming to and abutting against the curved bottom face of 10 said lip, said interlocked shank brace being provided with an overhanging support conforming to and extending from the curved bottom of said recess in the heel to form an extended seat for the outer sole. 15
